UNITED STATES PATENT OFFICE

DONALD D. WHITACRE, OF WAYNESBURG, AND JOHN C. WOOD, OF LAKewood, OHIO

WALL CONSTRUCTION

Application filed May 5, 1928. Serial No. 275,313.

This invention relates to wall construction and particularly to a composite wall formed of brick and hollow tile.

In current practice of building composite brick and tile walls, it has been the teaching of the prior art to bond the brick and tile together in, for instance, every sixth course by laying one course of brick endwise relative to the face of the wall so that these 10 bricks, which are commonly termed "header bricks," extend into the tile portion of the wall about half their length. In this practice about one-seventh of the mass of face brick are disposed in the tile portion or vertical tile zone of the wall.

Face brick for walls are sought among other reasons for their decorative value and since the appearance of the wall and building depends upon the quality of the brick, it 20 is often desirable to use an expensive face brick to enhance the appearance of the building. While expensive brick are used for the sake of appearance, it has been pointed out above, that the common practice 25 involves hiding about one-seventh of the total mass of brick as bonding elements in the form of header bricks. It is among the objects of our invention to eliminate this loss of face brick, to reduce the cost of the wall 30 and to substitute the less expensive hollow tile as the bonding unit between the brick and tile portion of the wall.

In constructing wall, it is good practice to lay the bricks on their sides with the 35 brick portion of the wall about four inches thick so that the brick facing will offer adequate resistance to the elements. We appreciate that the total tonnage of bricks used in a given wall could be reduced by reducing the thickness of the brick portion of the wall, but it is among the objects of our invention to effect an economy of brick without sacrificing the protective value of the brick facing or without reducing the thickness 40 of the brick part of the wall at least in the usual stretcher courses.

An object of our invention is to provide a wall in which the tile portion of the wall 45 comprises a plurality of like blocks so that the mason will not have to choose between

different tile blocks in laying the wall. Another object of our invention is to construct a wall of like units of tile with like units of brick while carrying out the above objects. A further object is to construct the 55 tile block with portions extending into the brick portion of the wall and bonding the two portions of the wall together to lend it strength.

Other objects will appear from the following description of the preferred form of our invention, reference being had to the accompanying drawings. While we have illustrated our invention in an environment of the common six course bond, those skilled 60 in the art will appreciate that the benefits of the teaching of our invention are not so limited.

In the drawings, Fig. 1 is a perspective of a section of the wall made in accordance 70 with our invention; Fig. 2 is a perspective view of a modified form of our invention; Fig. 3 is a perspective view of another modification of our invention; Figs. 4, 5 and 6 are perspective views of the tile blocks 75 shown in Figs. 1, 2 and 3 respectively.

Referring to Fig. 1, we show a preferred form of our invention in which two hollow back-up tile U (see also Fig. 4) are used for every six courses of brick. Each of the 80 back-up tile U have an outwardly extending lip M which extends into the brick portion of the wall and serves to bond the brick and tile portions together. In this form of our invention, however, we propose to use five 85 courses of stretcher brick S laid in the usual manner, but in every sixth course we propose to edge-set a brick S', which is otherwise equal to a stretcher brick S. The bricks S and S' are the same in size but the 90 bricks S lie on their greatest longitudinal surface while the bricks S' repose on their least longitudinal surface. In this arrangement each lip or extension M of the tile blocks U will have a depth equal to one- 95 half of the width of a brick less one-half a mortar joint, giving in standard practice, about two inches.

In this form of our invention the height of six courses of brick including a course 100

of edge-set brick is greater than the usual six courses with headers by the difference between the width and thickness of a brick. The economy of our construction may more 5 simply be shown by contrasting the structures of Fig. 2 with the well known and usual prior art construction.

Referring particularly to Fig. 2, we show a wall comprising the usual stretcher brick 10 S laid in five adjacent courses. We show adjacent the stretcher bricks on the inner side of the wall, a hollow tile block T. The tile block T is provided with an outwardly extending lip L which extends into 15 the brick portion of the wall and serves to bond the brick portions and the tile portions together.

To provide a uniform facing for the wall, veneer bricks B are laid against the lip of 20 the tile T and are bonded between courses of stretcher brick above and below. The veneer bricks V have the same vertical displacement as the stretcher bricks S.

In the present practice of building composite brick and tile walls wherein courses 25 of stretcher brick are laid between courses of header brick. The header brick extend into the tile of the zone of the wall. Thus the inner halves of the stretcher brick comprise substantially one-seventh of the total 30 mass of brick used in the wall. In contrasting this construction with the construction of Fig. 2, it will appear that not only is this one-seventh of the mass of brick eliminated from our wall, but in addition thereto, there is saved about one-half of the mass 35 of brick in the veneer course, i. e. in every sixth course, which amounts to a little more than one-twelfth of the total mass of brick. 40 Thus the saving in brick effected by the construction of Fig. 2 over the prior art construction is substantially one-seventh plus one-twelfth or about 22½% of the total amount of brick. For this much brick there 45 must be substituted an equivalent gross volume of tile, and inasmuch as the cost of tile per ton is greatly less than the cost of brick, there will be a very substantial saving in the total cost of material.

50 In addition to the saving in material, there will be a saving in labor and in handling, because one veneer brick will be substituted in the wall for two header brick so that instead of using seven bricks per unit 55 of wall surface, that is five stretcher brick and two header brick, there will be used but six brick for the same unit of wall surface, so that the time required for laying the wall should be reduced by about 60 14%.

In comparing Figs. 1 and 2, it can be seen that if the veneer brick B had the same horizontal dimension as the edge-set bricks S' that the saving in brick tonnage, effected 65 by the construction of Fig. 1 would be great-

er than that of Fig. 2. The veneer brick V may have a lesser horizontal dimension than edge-set brick S' so that the economy of material in the two forms may be substantially equal. We prefer the construction of Fig. 1 because it permits the use of 70 but two shapes of material, i. e. like bricks and like hollow tile blocks. The fewer the shapes the more rapidly they can be laid in the wall.

It will be understood that if it be desired to use edge-set bricks instead of veneer bricks in the construction shown in Fig. 1, that the depth of the lip L of the blocks T can be increased for this purpose. In 80 that event, the depth of the lip L would be equal substantially to the width of a stretcher brick.

A further modification of our invention is shown in Fig. 3, wherein tile blocks V (see 85 also Fig. 6) are used behind every five courses of stretcher brick. The tile blocks V are each provided with projecting lips N which extend outwardly to the face of the wall and entirely displace the header 90 or veneer brick, as the case may be. In this construction the appearance of the wall depends upon the color selection of brick and tile, and the practical extent of its use is 95 limited thereby.

It will appear from the foregoing that 100 wall constructed in accordance with the teaching of our invention can be constructed with an economy not heretofore possible; that the economy is effected without sacrifice of strength, appearance or durability of the finished wall; that in the completed wall a firm bond is established between the brick and tile portions; that the total tonnage of 105 brick in a given wall is greatly reduced and that the total mass of the whole wall is reduced. In a steel frame building the mass of steel necessary to support the walls is also reduced. With reference particularly to the construction shown in Figs. 1 and 3, 110 uniform tile shapes and uniform brick shapes may be used throughout the wall so that the mason will not be called upon to 115 select various shapes as he lays the units in the wall.

While we have illustrated and described a limited number of the forms of our invention and have pointed out the preferred form thereof, we do not care to be limited in the scope of our patent other than by the 120 claims appended hereto.

We claim:

1. A composite brick and tile wall, comprising face brick laid in a plurality of 125 stretcher courses, tile blocks behind the face brick having integrally formed lips extending into the brick facing portion of the wall between stretcher courses of brick, and brick units disposed with a lesser lateral dimension than the width of the stretcher brick 130

and comprising part of the wall facing and lying flush with the face of the wall and disposed horizontally adjacent said tile lips between said first named stretcher courses of brick.

- 5 2. A composite brick and tile wall, comprising face brick laid in a plurality of stretcher courses, L-shaped back-up tile having portions corresponding to the base of the L extending into the brick portion of the wall and having portions corresponding to the upright portion of the L lying behind the courses of stretcher brick, said L-shaped back-up tile being arranged base to base and head to head so that pairs of adjacent back-up tile have adjacent integrally formed portions extending into the brick portion of the wall and bonding the brick with the tile in the wall, and other bricks arranged flush with the face of the wall and disposed between stretcher courses of brick adjacent the base portions of the L-shaped back-up tile.
- 10 3. A wall construction comprising a brick facing portion with stretcher courses composed of brick laid on their sides in the usual manner and courses of edge-set brick set with one side flush with the face of the wall and disposed between stretcher courses, and
- 15 30 a tile back-up portion comprising hollow tile blocks having vertically extending portions disposed behind the stretcher courses of brick and having integrally formed horizontally extending portions which abut the inner sides of the said edge-set brick and extend between stretcher courses and bond the brick and the tile portions of the wall together.

- 40 4. A wall construction having a plurality of stretcher courses of brick arranged between intermediate courses of brick disposed with a lesser lateral dimension than the lateral displacement of the stretcher courses, said wall having a tile part composed of like L-shaped blocks having flat horizontal surfaces and arranged in pairs base to base and head to head the bases of the L-shaped blocks including integrally formed projecting parts of which a pair plus a mortar joint equal the height of the bricks in the intermediate courses between stretcher courses and extend into the brick part of the wall between stretcher courses adjacent the intermediate courses and bond the brick and tile parts of the wall together.

- 45 5. A wall construction comprising a hollow tile part generally arranged in a vertical zone constituting the inner part of the wall and being formed of like hollow tile blocks each having a major voided portion disposed within the tile zone of the wall and a minor voided portion extending beyond the tile zone toward the outer face of the wall, and being as high as half the width of a brick less half a mortar joint, said

blocks each having a major and a minor horizontal load bearing surface the major surface including one side of the said minor portion of the block, said blocks being arranged in pairs with major and minor surfaces of adjacent blocks spaced only by a horizontal mortar bed whereby the said minor portions of adjacent blocks lie together and comprise a lip or ledge equal in height to the width of a brick and extending beyond the tile zone of the wall, said wall having in addition to the tile part a brick facing part comprising stretcher courses of brick laid on their sides and defining generally a vertical brick zone adjacent the said tile zone, said brick part of the wall having edge-set brick in spaced courses between stretcher courses each equal in size to the stretcher brick and laid flush with the face of the wall in courses adjacent the outer faces of the said minor portions of the tile, whereby the stretcher courses of brick bond between them the edge-set brick and the part of the tile extending into the brick zone of the wall.

6. A composite brick and tile wall having a brick facing zone including face brick laid in a plurality of stretcher courses and having a tile back-up zone disposed behind the face brick and bonded with the bricks of the brick zone of the wall, the tile zone of the wall including blocks having integrally formed parts extending into the brick facing zone of the wall between stretcher courses of brick, the brick facing zone of the wall including brick units arranged in courses between stretcher courses and disposed with a lesser lateral dimension than the width of the stretcher brick and comprising part of the wall facing and lying flush with the face of the wall and disposed horizontally adjacent said tile parts between said first named stretcher course of brick whereby said tile parts bond the brick and tile zones of the wall together.

In testimony whereof, we hereunto affix our signatures.
